UNITED STATES PATENT OFFICE

HARRY L. MYERS, OF TOLEDO, OHIO, ASSIGNOR TO THE AMERICAN FLOOR SURFACING MACHINE CO., OF TOLEDO, OHIO

DESIGN FOR A CASING, MOTOR, AND HANDLE ENSEMBLE FOR A DRUM SANDING MACHINE

Application filed April 9, 1931. Serial No. 39,411. Term of patent 14 years.

To all whom it may concern:

Be it known that I, HARRY L. MYERS, a citizen of the United States, residing at Toledo, in the county of Lucas and State of Ohio, have invented a new, original, and ornamental Design for a Casing, Motor, and Handle Ensemble for a Drum Sanding Machine, of which the following is a specification, reference being had to the accompanying drawings, forming part thereof.

In the drawings:—

Figure 1 represents a side elevation.

Fig. 2 is a top plan view.

Fig. 3 is a side elevational view, showing the reverse side of the structure seen in Fig. 1.

Fig. 4 is a front end elevational view showing my new design.

I claim:—

The ornamental design for a casing, motor and handle ensemble for a drum sanding machine, as shown.

HARRY L. MYERS.
